CLAIM

The ornamental design for a gun cleaning brush kit case, as shown and described.

DESCRIPTION

FIG. 1 is a front, bottom and right side perspective view of a gun cleaning brush kit case, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view shown in a closed position. The broken lines in the drawings illustrate the portions of the gun cleaning brush kit case, which form no part of the claimed design.

1 Claim, 8 Drawing Sheets
